UNITED STATES PATENT OFFICE.

CHARLES E. PIERCE, OF CAMBRIDGE, MASSACHUSETTS.

INCANDESCENT LAMP.

1,131,079.

Specification of Letters Patent.

Patented Mar. 9, 1915.

Application filed November 5, 1913. Serial No. 799,391.

To all whom it may concern:

Be it known that I, CHARLES E. PIERCE, a citizen of the United States, and a resident of Cambridge, county of Middlesex, State 5 of Massachusetts, (whose post-office address is 200 Devonshire street, Boston, Massachusetts,) have invented an Improvement in Incandescent Lamps, of which the following description, in connection with the accompanying drawings, is a specification, 10 like characters on the drawings representing like parts.

This invention relates to improvements in incandescent lamps, having for its object 15 the provision of a lamp so constructed as to prevent or render commercially impracticable its renewal,—or, in other words, the substitution or attempted substitution of a new filament for the old one when the latter 20 is burned out or otherwise rendered useless or inefficient.

The invention will be best understood by reference to the following description when taken in connection with the accompanying 25 illustration of one specific embodiment thereof, while its scope will be more particularly pointed out in the appended claims.

In the drawings: Figure 1 is a side elevation of a lamp embodying one form of the invention, the walls of the bulb being partly broken away to show the filament support more distinctly; Fig. 2 is a sectional detail showing the prolongation of the filament support as it is used for exhausting the 35 lamp; and Fig. 3 is a similar view showing another modification of the invention.

Referring to the embodiment of the invention shown in Figs. 1 and 2, the same is shown applied to a lamp of ordinary construction but of a type employing a tungsten or similar filament. The lamp there shown is provided with the usual glass bulb 1 cemented or otherwise secured in the usual fashion to and within the metal base 2 and 45 having a common form of glass stem 3 through which pass the leading-in wires 4, which latter are joined to the ends of the filament 5. As is usual in this class of lamps the filament is supported by two sets of arms 6 and 7 extending laterally from a centrally arranged filament support 8 carried by and extending from the stem 3. The support 8 is used in the form of a glass rod welded to the stem and extending toward but terminating short of the tip 9 of the lamp bulb.

In renewing a lamp of this type, it is customary to make a small opening at the tip of the bulb, the opening being large enough to insert instruments whereby the old filament may be withdrawn and replaced by a new one. A small glass tube is then welded to the bulb at the point where the opening has been made, the bulb exhausted, and the tip again sealed off as when first manufactured. It is impracticable, however, to make this opening larger than a certain minimum; otherwise the labor cost of patching over the large opening and welding on the tube would be greater than the cost of manufacturing a new bulb. In the illustrative embodiment of my invention this fact is taken advantage of by so constructing the bulb at or adjacent its tip that entrance to the interior of the bulb cannot be had through the tip.

Referring to Figs. 1 and 2, the filament support 8 has a short prolongation 10 beyond the arms 7 and telescopically secured on this prolongation is the tubular extension member 11. The latter extends to and is connected to the bulb 1 at the inside of the tip 9 so that a perforation sufficient to renew the filament must either be at one side of the tip or of such size as to be impracticable.

The extension 11 may be tubular in form 85 and utilized to exhaust the bulb in place of the tubular stem which is customarily fastened to the lamp bulb prior to exhaustion. To this end the bulb 1 (see Fig. 2) may have welded thereto the tubular exhaust stem 12 when the bulb is assembled on the base 2. The tubular exhaust stem 12 is prolonged within the bulb to form the extension member 11 of such size and so positioned as to fit over the prolongation 10 95 on the filament support 8. One or more lateral openings 13 being provided in the extension member 11, the bulb is then exhausted through the tube 12 by connecting the same to the exhaust pipe 14, carrying 100 out the usual process of exhaustion after which the exhaust stem 12 is closed and sealed off to form the tip 9 in the usual way. The attachment of the extension member to the tip of the bulb as described gives 105 additional rigidity and strength to the filament support 8.

In Fig. 3 a modified form of the invention is shown wherein entrance through the bulb tip is prevented by means of an obstruction 110

member 15 in the form of a plate carried by an extension 16 of the filament support 17.

While I have herein shown and described for purposes of illustration one specific embodiment of the invention, it is to be understood that the same is not limited to the details of construction and relative arrangement of parts but that extensive deviations may be made therefrom without departing 10 from the spirit thereof.

Claims:

1. A non-renewable incandescent lamp having a bulb provided with a tip projecting from the bulb, a base, a centrally arranged filament support extending from the stem, laterally extending supporting arms on said support, a filament carried thereby, and a prolongation of the filament support 20 extending to and connected with the bulb to prevent entrance through the tip for purposes of renewal, the termination of said prolongation having a cross sectional area at least as great as that of the projecting tip, thereby overlying the entire tip, and thus preventing renewal of the filament.

2. A non-renewable incandescent lamp having a bulb provided with a tip projecting from the bulb, a base, a stem, a centrally arranged filament support extending from the stem, a filament, and a prolongation on said support preventing entrance to

the bulb through the tip for purposes of renewal, the termination of said prolongation having a cross sectional area at least 35 as great as that of the projecting tip, thereby overlying the entire tip, and thus preventing renewal of the filament.

3. A non-renewable incandescent lamp having a bulb, a base, a stem, a centrally arranged filament support extending from the stem, and a tubular prolongation secured to the end of the filament support, said prolongation having lateral openings within the bulb whereby a projection of 45 said prolongation may be employed to exhaust the lamp prior to sealing off.

4. A non-renewable, incandescent lamp having a bulb, a base, a stem, a centrally arranged filament support extending from 50 the stem, and a tubular prolongation secured to the end of the filament support, said prolongation having communication with the interior of the bulb, whereby the projection of said prolongation may be employed to 55 exhaust the lamp prior to sealing off.

In testimony whereof, I have signed my name to this specification, in the presence of two subscribing witnesses.

CHARLES E. PIERCE.
